(57) CLAIM

The ornamental design for a shampoo bowl, as shown and described.

DESCRIPTION

FIG. 1 is a first perspective view of a shampoo bowl showing my new design;

FIG. 2 is a second perspective view of the shampoo bowl of FIG. 1 showing my new design;

FIG. 3 is a front view thereof;

FIG. 4 is a back view thereof;

FIG. 5 is a first side view of the shampoo bowl of FIG. 1, the second side view being identical and a mirror image thereof;

FIG. 6 is a top view thereof; and,

FIG. 7 is a bottom view thereof.

The dotted lines are intended to show features that are environmental only and form no part of the claimed design.

1 Claim, 4 Drawing Sheets
